BURIAL VAULT

Filed Nov. 1, 1937

FIG. 1.

FIG. 2.

FIG. 3.

FIG. 4.

INVENTOR:

Walter C. Broughton,

F. G. Fischer,

ATTORNEY.

UNITED STATES PATENT OFFICE

2,135,559

BURIAL VAULT

Walter C. Broughton, Kansas City, Mo.

Application November 1, 1937, Serial No. 172,166

1 Claim. (Cl. 72—7)

My invention relates to burial vaults and one object is to provide a durable structure of this character having inner and outer chambers with an intervening water-proof core to exclude air, water, or moisture from the inner chamber in which the casket is placed.

A further object is to provide novel means for hermetically sealing the joints between the lid and the inner and outer chambers to prevent the entrance of water or the escape of the products of decomposition.

Another object is to provide a burial vault which is free from projections likely to become damaged while being molded or transported.

15 Other objects will hereinafter appear, and in order that the invention may be fully understood reference will now be had to the accompanying drawing, in which:

Fig. 1 is a perspective view of the burial vault.
20 Fig. 2 is a longitudinal sectional view of the burial vault.

Fig. 3 is a cross section on line 3—3 of Fig. 2.
Fig. 4 is a broken cross section with the lid raised above the body of the vault.

25 In carrying out the invention I provide a body portion comprising inner and outer chambers 2 and 10, respectively. The inner chamber 2 is preferably made of cement or concrete and comprises a bottom wall 4, end walls 6 and side walls 8.

The outer chamber 10 is preferably made of the same material as the inner chamber 2 and comprises a bottom wall 12, end walls 14 and side walls 16.

30 The outer chamber 10 is of such size as to leave an intervening space between it and the walls of the inner chamber 2 for the reception of a core 18 consisting of asphalt or other water-proof material.

35 In practice the inner chamber 2 is preferably cast in one piece and coated with the water-proof material 18 over which the outer chamber is then cast preferably in one piece. When the body of the vault is thus completed the end and side walls 6 and 8, respectively, of the inner chamber 6 project above the corresponding walls of the outer chamber 10 to provide a continuous flange 20.

40 22 designates the lid of the vault which is preferably arch-shaped and made of the same material as that comprising the body of the vault. As shown by Figs. 2 to 4, inclusive, the lid 22 comprises an inner section 24 and an outer section 26, with an intervening core 28 of water-proof material.

45 The end and side walls 27 and 29, respectively, of the outer section 26 extend below the corresponding walls of the inner section 24 to provide a continuous flange adapted to telescope

over the flange 20 of the inner chamber 2 when the lid 22 is lowered into position over the body of the vault.

5 On completion of the body of the vault the water-proof core 18 is spread over the upper margin of the outer chamber 10 and the outer surface of the flange 20, then beveled off as indicated at 30, Fig. 4, so that when the lid 22 is lowered upon the body the water-proof material 18 will be compressed as indicated at 31, Figs. 2 and 3, and thus hermetically seal the joint between the body 10 and the outer section 26 of the lid.

10 As a further precautionary measure the lower portion of the water-proof core 28 is spread over the lower margin of the inner section 24 of the lid and the inner surface of the walls 27 and 29, then beveled as indicated at 32 to provide sufficient body to hermetically seal the joint between the lower margin of the section 24 and 20 the upper margin of the flange 20, as indicated at 33, Figs. 2 and 3.

15 From the foregoing it will be understood that the complete structure provides in effect a triple wall, triple seal burial vault consisting of concrete or other durable material and having a core of water-proof material completely surrounding and enclosing the bottom, side and end walls of the inner or casket chamber 2, and a water-proof core surrounding the inner section of 30 the lid, thereby providing an air-tight, water and vermin-proof tomb which may be regarded as everlasting, and while I have shown a preferred form of my burial vault I reserve all rights to such forms and modifications thereof as properly fall within the spirit and scope of the invention as claimed.

35 Having thus described my invention, what I claim and desire to secure by Letters Patent is:

40 A burial vault comprising a body portion and a lid therefor, said body portion comprising inner and outer chambers respectively with an intervening core of waterproof material, the walls of said inner chamber projecting above the walls of the outer chamber to provide an upwardly extending flange, said waterproof material extending upwardly to a level with the top of the flange and overlapping the upper edges of the end and side walls respectively of the outer chamber, the lid for the body portion comprising inner and 45 outer sections with an intervening waterproof core, said outer section extending below the inner section and adapted to telescope over the upwardly projecting flange of the body, and said waterproof core extending downward to the lower 50 margin of the outer section and covering the lower margin of the inner section.

55 WALTER C. BROUGHTON.
